(57) **CLAIM**

The ornamental design for a display screen or portion thereof with animated graphical user interface, as shown and described.

DESCRIPTION

FIG. 1 is a front view of a display screen or portion thereof with animated graphical user interface showing a first view of five views;

FIG. 2 is a front view thereof showing a second view of five views;

FIG. 3 is a front view thereof showing a third view of five views;

FIG. 4 is a front view thereof showing a fourth view of five views; and,

FIG. 5 is a front view thereof showing a fifth view of five views.

The broken lines in the figures illustrate a mobile device, which is the environment of the design, and which forms no part of the claimed design. The remaining broken lines illustrate portions of the display screen and portions of the graphical user interface, and form no part of the claimed design.

The appearance of the image transitions sequentially between the images shown in FIGS. 1-5. The process or period in which one image transitions to another forms no part of the claimed design.
